UNITED STATES PATENT OFFICE.

JACOB FLEISCHMAN, OF CHICAGO, ILLINOIS.

COMBINATION TOOL.

Application filed July 16, 1926. Serial No. 122,907.

This invention relates to combination tools, and its object is to provide in a compact and handy article a number of tools suitable for carpentry, cabinet making and similar work.

A further object of the invention is to provide it with means for laying out or measuring special work.

A still further object of the invention is to construct the same in flat, elongated form, so that it may be conveniently carried in a long, narrow overalls pocket, like a folding rule.

A final, but nevertheless important object of the invention is to construct the same of few and simple parts and with no projections to catch in the clothes or cause discomfort.

With the above objects in view, a better understanding of the invention may be had by reference to the accompanying drawings, in which—

Figure 1 is a perspective view of the appliance as viewed from one side;

Fig. 2 is a like view, taken from the other side;

Fig. 3 is a longitudinal section;

Fig. 4 is a plan view illustrating the more common uses of the invention;

Fig. 5 is a perspective view showing a cabinet installation requiring a special use of the tool;

Fig. 6 is a sectional group of the fittings used in the cabinet installation referred to;

Figs 7 to 10 are perspective views illustrating other instances of the special application of the tool; and

Fig. 11 is a section on line 11—11 of Fig. 1.

Referring specifically to the drawings, 15 denotes the stock of the tool, which is of flat steel and is adapted to contain the parts contributing to the various uses of the tool. One such part is an arm 16, seated in a cavity 17 in one edge of the stock. One end of the arm 40 is perforated for pivotal motion about a screw 18 applied from one side of the stock. The arm may thus be swung out to form a right angle with the stock for use as a try-square; or it may be fixed at any intermediate 45 angle by tightening the screw 18 to form an angle or mitering gage. The heel of the arm is square, as shown at 16^a, so that the arm may seat accurately at 90 degrees when 50 swung at right-angles to the stock, and go no further, this adjustment being fixed by tightening the screw 18. For the intermediate

angles, readings are taken from a bow 19 carried by the arm and moving in a slot 20 in the stock. The bow 19 is pivotally attached with one end to the arm as shown at 21 and is 60 foldable into a pocket 16^b of the arm when the tool is not in use.

The opposite or outer end of the arm 16 is tapered and fitted with a point 16^c to serve as a compass with a companion arm 22 65 slideable in a cavity 23 of the stock and stationed at any position by a set-screw 24. The outer end of the rod has a projecting point 22^a for compass use; and a point 22^b projects from the side of the rod for use in conjunction with 70 the stock as a scratch-gage. Also, the rod is forked at 22^c to clear the bow 19 when in use.

The above constitute the common or ordinary uses of the tool, that is, as a try-square, angle or miter gage, compass and 75 scratch gage. The special applications of the tool will now be taken up.

Figure 5 shows a cabinet whose frame and door are fitted with co-operating devices constituting a spring latch to retain the door 80 when in closed position. This type of latch is widely used on talking machine, radio and other cabinets, but the method of preparing the cabinet frame and doors for the installation of the latch has so far been laborious and 85 frequently inaccurate. The special features of the novel combination tool are designed to accomplish the work quickly and accurately, so that the process becomes an efficient one.

The co-operating fittings constituting the latch are shown more clearly in Fig. 6, and comprise a keeper plate 25 carried by the door and a spring plunger 26 mounted in the ceiling of the cabinet. The keeper plate has 95 an inclined approach 25^a for the plunger, a depression 25^b to seat the latter, and an aperture 25^c in the depression to receive a nail when fastening down the plate. The edge of the plate at the approach is flat and aligned 100 with the inner edge of the door when the plate is laid. The plunger 26 is set in a cup 26^a and backed by a spring 26^b. The cup is driven into a bore 27 (see Fig. 9) in the ceiling of the cabinet, and the plunger yields to 105 the plate when the door is closed.

In preparing for the installation of the latch in a single door cabinet, such as in Fig. 9, it is generally found that the ceiling bore 27 has been properly drilled before the assembly 110 of the cabinet, so that it is only necessary to match the site of the bore on the top edge of

the door. To do this, a strip 28 slidable in a channel 29 in one edge of the stock 15 is employed. The strip is longitudinally slotted at 28^a and is held in place at any longitudinal 5 adjustment by a screw 28^b passing through the slot into the stock. The outer end of the strip has a dowel-stud 28^c projecting from its inner face. When the tool is positioned and the strip extended over the door as per Fig. 10 9, the tool may be tilted to hook the dowel-stud 28^c in the ceiling bore 27 as the door is almost closed. A pencil or screw driver may now be inserted in the slot 28^a to make a cross-mark on the door. With this mark indicated 15 as in Fig. 10, an auger bit is applied so as to cut a shallow cavity bordering on the inner edge of the door, as denoted by the circular dotted line. A keeper plate can now be set in this cavity by a sharp blow of a hammer; and 20 when a plunger unit is driven into the bore 27, the latch is ready for use. If the latch is found to function properly, the keeper plate may be permanently secured by a nail, as previously mentioned.

25 The above operation applies to single-door cabinets in which the ceiling bore (27) for the plunger unit was found already made. In cabinets having double doors which meet at the center it is preferable to drill the bores 30 when the latches are fitted, and in this connection another feature of the novel tool comes into use.

In the plotting of a center point for the ceiling bore of each door, two dimensions are 35 considered, viz the distance from the closing-edge of the door, and that from the closing face thereof. The tool is set for these distances, and then applied to the ceiling of the cabinet for the marking thereof. Taking 40 the tool, it will be noted that beyond the heel of the arm 16, the stock is transversely bored at 30 to seat a slidable block 31, stationed by a set screw 32. When the block is in outwardly-projected position and the arm 16 is set 45 at right-angles to the stock, as indicated in Fig. 8, the block is used as an origin from which to space an aperture 33 in the arm. Different spacings may be secured by removing the pivot-screw 18 and setting the arms 50 opposite any one of a series of tapped holes 18^a in which the screw may again be fitted. The stock may be graduated to denote the spacing of the holes 18^a from the origin block 31. As to the arm aperture 33, its spacing 55 from the edge of the stock corresponds to the spacing desired for the ceiling bore center in an outward direction from the inner face of the closed door.

In order to plot the bore center, the tool— 60 with the arm 16 closed but the block 31 projected—is laid next inside the closed door and flatly against the ceiling, with the block 31 abutting the edge of the door, as clearly shown in Fig. 7. With the tool seating 65 against the door and held firmly to the ceil-

ing at the same time with one hand, the door is swung away with the other hand, and the arm 16 swung out, as shown in Fig. 8. An awl passed up through the aperture 33 will make the proper center point in the ceiling. 70 The bore 27 may now be drilled and the balance of the work done in the manner described in connection with the single door. To plot the center point for the adjacent door, the tool is applied in the same fashion, 75 but of course in inverted position.

The latch is marketed in two sizes, and for this purpose, an additional arm aperture 33^a is provided and properly spaced, to change the position of the bore 27 relative to that 80 which will be occupied by the different-sized keeper plate.

A tool is thus had which is compact in form and contains a number of units which are applicable both to ordinary and special cabinet 85 work. The stock is machined flat and the set-screws sunken so that the sides of the tool will have no projections to catch in the mechanic's clothes. For facility, the scratch gage rod 22 will be marked with indications, so that it 90 may be accurately set to any position desired. Also, the set screw 18 should be constructed in accordance with Fig. 11. The shank 18^c is threaded through one wall of the stock 15, then reduced to a stem 18^b which passes 95 through the arm 16, and finally lodged in a recess 18^c in the other wall of the stock. The shank thus bears with a shoulder against the arm when the screw is in the advanced position shown. The top and recess in the walls 100 are of course duplicated in a series for setting the arm over in one or the other direction.

I claim:

1. A tool comprised of a long stock, the latter having an open recess cut from one end and a bore made from the same end in spaced relation to the recess with a crossbore through the stock intersecting the recess and the bore, an arm seated in the recess, said arm being pivotally mounted in the stock and having a pocket in its inner edge, a set screw in the pivot, the stock having means adapted to receive the set screw and arm at different points in the direction of the length of the stock, a rod slidably seated in the bore and recessed to 105 clear the crossbore, and a bow housed in and pivotally secured in the pocket and adapted to be swung out to travel in the crossbore 110 during the pivotal adjustment of the arm 115 relative to the rod.

2. A spacing gage comprising a stock having a longitudinal recess in one side edge, an arm pivoted in said recess to swing laterally through an arc of ninety degrees relative to the stock, means for adjusting the pivotal point of said arm longitudinally of the recess, said stock having a transverse bore at one end of said recess, a member longitudinally slidable over the opposite side edge of the stock 125 and closing one end of said transverse bore, a 130

slidable abutment disposed in said transverse bore, a bow pivotally connected with said arm inwardly of the stock, and said stock and said member being apertured for reception of the bow therethrough.

3. A spacing gage comprising a stock having a longitudinal recess in one edge, an arm disposed in the recess and pivotally mounted to swing out of the recess to a position at right-angles to the stock, a set screw in the

pivot to fix the arm in the said position, one wall of the recess having a longitudinal series of tapped holes through which the set screw is selectively insertable to move the pivot to any position along the stock, and an abutment at one end of the stock from which the spacing of the selected position of the arm is measured.

In testimony whereof I affix my signature.
JACOB FLEISCHMAN.
